United States Patent Office

Des. 202,311
Patented Sept. 14, 1965

202,311

AIRCRAFT

Lawrence Bernard Rellis, La Mesa, Calif.
(3317-1 Cowley Way, San Diego, Calif.)

Filed Mar. 23, 1964, Ser. No. 79,130

Term of patent 14 years

(Cl. D71—1)

Fig. 1

Eg-4

Eg-3

FIG. 1 is a perspective view of the aircraft showing my new design;

FIG. 2 is a top plan view thereof;

FIG. 3 is a front elevational view thereof with the wheels in lowered position;

FIG. 4 is a rear elevational view of FIG. 3;

FIG. 5 is a bottom plan view with the wheels retracted; and

FIG. 6 is a side elevational view of FIG. 3; the opposite side being shown in FIG. 1.

I claim:

The ornamental design for an aircraft, as shown and described.
